UNITED STATES PATENT OFFICE.

SINCLAIR J. JOHNSON, OF NUTLEY, NEW JERSEY.

FREIGHT-CAR.

SPECIFICATION forming part of Letters Patent No. 654,896, dated July 31, 1900.

Application filed January 9, 1900. Serial No. 813. (No model.)

To all whom it may concern:

Be it known that I, SINCLAIR J. JOHNSON, a citizen of the United States, residing in Nutley, in the county of Essex and State of New Jersey, have invented certain new and useful Improvements in Freight-Cars, of which the following is a specification.

This invention relates to freight-cars; and it more particularly relates to the construction of the door and the door-easing thereof, one object of the invention being to provide an improved door and doorway in which the swelling or expansion of the door and of the side walls of the car adjacent to the doorway will not interfere with the proper closing or opening of the door, while the contraction or shrinkage of the body or woodwork of either of said parts will not affect the proper size of the door or of the doorway.

A further object of the invention is to provide those edges of the door and of the car-wall adjacent to the doorway subject to the effect of swelling or shrinkage, usually the side edges of such parts, with means adapted to permit the swelling and contraction of the body or woodwork of the parts while always maintaining the same size of the door and its doorway.

A further object of the invention is to provide the body of a door and the car-wall at the doorway thereof with margin or boundary portions made of material not subject to shrinkage or swelling to a material degree, and each secured to a part free of appreciable shrinkage or swelling in a direction to shift the relations of the margin or boundary portions, each of said margin portions being constructed to overlap the side of its respective member to an extent sufficient to prevent the formation of an opening or gap intermediate such margin portion and the edge of its respective member when such member is shrunk to its greatest amount which occurs in practice.

In the drawings accompanying and forming part of this specification, Figure 1 is a side view of a portion of a car-body and one form of door supported thereon flush with the car-wall. Fig. 2 is a sectional view taken in line 2 2, Fig. 1. Fig. 3 is a cross-sectional view taken in line 3 3, Fig. 1, and looking downward. Fig. 4 is a detail view of a part of one

of the shaped ironis secured to the edge of the door and the car-wall adjacent to the doorway.

55

Similar characters of reference designate like parts in all the figures of the drawings.

In the manufacture and use of freight-cars it is a well-known fact that the swelling or expansion of the car-door and also of the car-wall at each side of the door is such that it is frequently necessary to use a crowbar in order to open the same, to the material injury of the door and its casing, it being practically impossible to provide a flush car-door that will not become wedged in the doorway or so swollen after the same has remained open for a short time as to prevent its fitting therein. At times also the shrinkage or contraction of the door and this part of the car-wall is such that a large opening or space is formed between the door and its casing. To avoid these objectionable features, I have provided means which when assembled with those edges of the door and car-wall contiguous to such doorway that are subject to the effect of swelling or shrinkage, usually the side edges thereof, furnishes an improved organization which permits the swelling and shrinkage of the body or woodwork of both the door and the car-wall, while always maintaining the same without affecting the proper size of the door or of the doorway, so that the opening or closing of the door is permitted at all times without interference and without the necessity of using a crowbar.

75

In the present structure the door is shown as being shiftable outward and upward into position to be moved on a track away from the doorway, it being understood, however, that other organizations may be used, if desired.

80

The means for moving the door from its flush position in the doorway into position to be moved away from such doorway is shown herein as substantially similar to that provided in my contemporaneously - pending application, filed July 31, 1899, Serial No. 725,642, and therefore a further description thereof is not deemed necessary, since the door-actuating means shown is not essential to the present improvement.

95

The door-easing comprises a door-lintel 2, a door-sill 3, both of some suitable construc-

tion, and door-posts 4, each of which posts is shown herein recessed or rabbeted in such manner that the ends of the cross-bars or battens 5 of the door (which are not subject to the effect of appreciable endwise swelling or shrinkage) will fit therein and permit the door to be flush with the side wall of the car.

The door-posts 4 are so secured at the top and bottom that the swelling or shrinkage thereof can only occur, if at all, adjacent to the middle, and even then it is not appreciable, the car-boarding being secured in position so as not to affect the position of such posts—as, for instance, by not directly attaching the boarding to such posts, so that it is free to work in the channel or other irons, hereinafter described.

The door, formed in some suitable manner and having the usual cross-bars or battens 5, has each edge subject to the effect of swelling or shrinkage, usually the side edges in the form of door shown herein, provided with means which while permitting the swelling or shrinkage of the body or woodwork of the door will always maintain the same size of the door as a whole, and which means in the present instance comprises a shaped iron (shown in one form thereof as a channel-iron or member 7) of some suitable material not appreciably affected by atmospheric changes—for instance, metal—one flange 7' of which channel-iron is shown herein wider than the other flange 7" thereof, whereby a relatively-wide bearing-surface is obtained for securing the iron in position. These channel-irons are secured to the door in such manner that the outer faces 8' of the webs 8 determine the proper width of the door and will preferably be flush with the ends of the battens, the flanges 7' being secured to the battens in the form of door shown and intermediate such battens and the inner side of the door, a space 8" being formed intermediate such web 8 and the edge of the door when the body or woodwork thereof is in its normal condition or contracted and which space is sufficient to permit the usual amount of swelling of the door-woodwork. The flange 7" is formed sufficiently wide to permit the usual amount of shrinkage or contraction of the body or wood-work of the door without the formation of an opening or gap intermediate the edge of the channel-iron flange and the edge of the door-woodwork. From the foregoing it will be seen that the body or woodwork of the door at the side edges thereof is inclosed by a pair of metallic casings, so that at no time will the swelling of such woodwork prevent the door from being readily shifted into position or out of the doorway, while the shrinkage of such woodwork will not decrease the proper size of the door as a whole. Since the swelling or shrinkage of the car-wall is usually considerable at the sides of the doorway, the edges or sides of such wall subject to the effect of swelling and shrinkage, and shown herein as the side edges there-

of, are also provided with channel-irons similar to those above described and each of which is secured to the posts 4 and intermediate the inner side of the wall and the door-post 4 in substantially the same manner as that above described to form a space a'', whereby the swelling and shrinkage of the woodwork of the car-wall can take place without increasing or decreasing the size of the doorway, so that the door can always be readily seated in its doorway or shifted out thereof without interference. The space 8" or 8" is shown in the present instance, owing to the particular-shaped iron used, as a closed space and is of sufficient area to permit the woodwork to swell or shrink to the usual extent without affecting the size of the doorway or door. From the foregoing it will be seen that the outer faces of the webs of the channel-irons of the door and doorway are comparatively close together, and when the wood-work shrinks no opening will be formed between such irons and the car, although the spaces 8" or 8" may be considerable. By the provision of this metallic casing for the door and car-wall it will be seen that the edges of such casing and door are protected from being splintered or broken and also from becoming worn, while the swelling and shrinkage of the body or woodwork of the door and of the car-wall are provided for, so that the door can always fit flush in the doorway without becoming wedged or jammed therein.

In conclusion I desire to state that, if preferred, shaped irons other than the channel-irons shown may be used and such channel or other irons may be secured in position in any desired manner to accomplish the purpose set forth.

It is to be understood that the channel-irons are secured adjacent to those edges of the door and car-wall that are subject to the effect of swelling or shrinkage, whether this be the side or top or bottom edges of the door or doorway, so that the term "side" or "edges" as used in the claims is to be read with this interpretation.

Having described my invention, I claim—

1. The combination, in a door, of a door-margin or boundary portion made of material not subject to shrinkage or swelling to a material degree and secured to a part free of appreciable shrinkage or swelling in a direction to shift the relations of the margin or boundary portion, and a body portion having free relation to such boundary portion or margin to permit the swelling or shrinkage of said body portion and adapted to engage such margin or boundary portion intermediate the outer and inner edges of such margin portion when in engagement therewith.

2. The combination, in a door, of a door-margin or boundary portion made of material not subject to shrinkage or swelling to a material degree and secured to a part free of appreciable shrinkage or swelling in a direction to shift the relations of the margin or bound-

ary portion, and a body portion having free relation to such boundary portion or margin to permit the swelling or shrinkage of said body portion, said margin lapping a side of 5 said body portion to an extent equal to the difference in dimensions of the door when swollen and when shrunk to the greatest amount which occurs in practice.

3. The combination, in a door, of a door-
10 margin or boundary portion made of material not subject to shrinkage or swelling to a material degree and secured to a part free of appreciable shrinkage in a direction to shift the relations of the margin or boundary portion, 15 and a body portion having free relation to such boundary portion or margin to permit the swelling or shrinkage of said body portion, said margin lapping both sides of said body portion to an extent equal to the difference 20 in dimensions of the door when swollen and when shrunk to the greatest amount which occurs in practice.

4. A car-door comprising a body and margin or boundary means comprising shaped 25 irons each secured to a part free of appreciable shrinkage or swelling in a direction to shift the relations of said margin or boundary means, and each in position to form a space intermediate thereof and said body when such 30 body is in its normal condition or contracted and adapted when in engagement with such body to engage it intermediate the outer and inner edges of said margin means.

5. A car-door the body of which has each 35 edge subject to the effect of atmospheric changes provided with a shaped iron secured in position free of such body and lapping the side of said body to an extent at least equal to the dimensions of the door when swollen 40 and when shrunk to the greatest amount which occurs in practice, whereby the door is permanently of the same size whether the body thereof be in a shrunken or swollen condition.

45 6. A car-door the body of which has each edge subject to the effect of atmospheric changes provided with a channel-iron secured in position free of such body and lapping the side of the body to an extent at least equal 50 to the difference in dimensions of the body when swollen and when shrunk to the greatest amount which occurs in practice, whereby the door is permanently of the same size whether the body thereof be in a shrunken or 55 swollen condition.

7. A car-door the body of which has each edge subject to the effect of swelling or shrinkage provided with a metallic device overlapping the inner and outer sides thereof to an 60 extent at least equal to the difference in dimensions of the body when swollen and when shrunk to the greatest extent which occurs in practice, thereby forming a space at the edge of such door when in its normal condition or contracted, said device having one part thereof of greater width than another part thereof.

8. A car-wall having a doorway and a doorway margin or boundary portion made of material not subject to shrinkage or swelling to 70 a material degree and secured to a part free of appreciable shrinkage or swelling in a direction to shift the relations of the margin or boundary portion, said wall having free relation to such boundary portion, the organization being such that the same size of the doorway is permanently maintained whether the car-wall be in a shrunken or swollen condition. 75

9. A car-wall having a doorway and a doorway-margin or boundary portion made of material not subject to shrinkage or swelling to a material degree and secured to a part free of appreciable shrinkage or swelling in a direction to shift the relations of the margin or 80 boundary portion, said wall having free relation to such boundary portion, and said margin lapping a side of said wall to an extent at least equal to the difference in dimensions of the door when swollen and when 85 shrunk to the greatest amount which occurs in practice, the organization being such that the same size of the doorway is permanently maintained whether the car-wall be in a shrunken or swollen condition. 90

10. A car-wall having a doorway and a doorway-margin or boundary portion made of material not subject to shrinkage or swelling to a material degree and secured to a part free of appreciable shrinkage or swelling in a direction to shift the relations of the margin or boundary portion, said wall having free relation to such boundary portion, and said margin lapping both sides of said wall to an extent at least equal to the dimensions of the 105 wall when swollen and when shrunk to the greatest amount which occurs in practice, whereby the same size of the doorway is permanently maintained whether the car-wall be in a shrunken or a swollen condition. 110

11. A car-wall constructed of timber and provided with a doorway having each edge thereof contiguous to such doorway and subject to the effect of swelling or shrinkage provided with fixed or non-movable means in- 115 closing the woodwork at such edge to an extent sufficient to prevent the formation of a gap or opening between said means and the edge of the wall when under contraction, and thereby forming a closed space when such 120 wall is in its normal condition or contracted, the organization being such that the same size of the doorway is permanently maintained while providing for the swelling or shrinkage of the woodwork of the wall. 125

12. A car-wall having a doorway, a plurality of the edges of which wall contiguous to such doorway are provided with channel-irons, each so secured in position as to form a closed space between the web of such iron 130 and the edge of the wall when the latter is in its normal condition or contracted, and thereby prevent the formation of a gap or opening between such iron and the edge of the wall.

13. A car-wall having a doorway, each edge of which wall, subject to the effect of swelling or shrinkage, is provided with a metallic device overlapping the inner and outer sides 5 of such wall and forming a closed space at the edge thereof when the wall is in its normal condition or contracted, and thereby prevent the formation of a gap between such device and the edge of the wall, said device having one part of greater width than another part thereof.

14. A car-wall provided with a doorway and a door, each edge of which door and wall contiguous to such doorway and subject to the 15 effect of swelling or shrinkage, is provided with a channel-iron located to form a closed space at such edge when the woodwork is in its normal condition or contracted, and thereby prevent the formation of a gap between 20 such iron and the edge of such part.

15. A car-wall provided with a doorway and a door, each edge of which door and wall contiguous to such doorway and subject to the effect of swelling or shrinkage, is provided 25 with means located to form a space at such edge when the woodwork is in its normal condition or contracted.

16. A car-wall having a doorway each edge of which wall contiguous to such doorway and 30 subject to the effect of swelling or shrinkage is provided with a shaped iron so secured in position as to form a space between the web of such iron and the edge of the wall when such wall is in its normal condition or contracted.

17. A car-wall having a doorway and side posts and a doorway-margin portion free from a tendency to shrink or swell, secured to each 40 of said posts and effective to always maintain the same size of the doorway while permitting the swelling or shrinkage of said wall.

18. A car-wall having a doorway; a post located at each side of said doorway; and a shaped iron secured to each of said posts and 45 adapted to project in parallelism with the edge of such wall to always maintain the same size of the doorway while permitting the swelling or shrinkage of the car-wall.

19. A car-wall provided with a doorway having side posts lapped by said car-wall, and a 50

doorway-margin portion forming a jamb member free from a tendency to shrink or swell secured to each of said posts, each of said jamb members lapping the wall while free thereof so as to permit the swelling or shrinkage of 55 said wall while permanently maintaining the same size of the doorway.

20. The combination, in a door having battens or braces, of a door-margin or boundary portion made of material not subject to shrinkage or swelling to a material degree and secured to said battens or braces, and a body portion having free relation to such boundary portion or margin, said margin lapping a side of said body portion to an extent equal to the 65 difference in the dimensions of the door when swollen and when shrunk to the greatest amount which occurs in practice.

21. A car structure comprising a wall having a doorway, and a door therefor comprising a body, said doorway and body each having margin means free of material shrinkage or swelling and secured to parts free of appreciable shrinkage or swelling in a direction to shift the relations of said margin means, 75 said margin means being free of said wall and body, thereby to permit the swelling or shrinkage of said wall and body while permanently maintaining the same size of said door and doorway.

22. A car structure comprising a wall having a doorway, and a door therefor comprising a body, said doorway and body each having margin means free of material shrinkage or swelling and secured to parts free of appreciable shrinkage or swelling in a direction to shift the relations of said margin means, 85 said margin means being free of said wall and body, thereby to permit the swelling or shrinkage of said wall and body while permanently maintaining the same size of said door and doorway, and each such margin means overlapping its respective member, thereby to prevent the formation of a gap or opening between said margin means and said 90 member when such member contracts.

SINCLAIR J. JOHNSON.
